W. A. SPURRIER.
HOLDER FOR CALENDAR PADS AND THE LIKE.
APPLICATION FILED MAY 28, 1915.

Patented Feb. 6, 1917.

1,214,605.

Inventor:

William A. Spurrier:

By his Atty Charles S. Gooday

UNITED STATES PATENT OFFICE.

WILLIAM A. SPURRIER, OF NEWTON, MASSACHUSETTS.

HOLDER FOR CALENDAR-PADS AND THE LIKE.

1,214,605.

Specification of Letters Patent.

Patented Feb. 6, 1917.

Application filed May 28, 1915. Serial No. 31,086.

To all whom it may concern:

Be it known that I, WILLIAM A. SPURRIER, a citizen of the United States, residing at Newton, in the county of Middlesex and 5 State of Massachusetts, have invented new and useful Improvements in Holders for Calendar-Pads and the like, of which the following is a specification.

This invention relates to new and useful

10 improvements in holders for calendar pads and the like and has for its object to provide a holder which, by reason of its construction, may be made of exceedingly light sheet material, preferably metal, and yet be 15 substantial and neat in appearance and inexpensive to manufacture.

The invention consists in the combination and arrangement of parts set forth in the following specification and particularly 20 pointed out in the claims.

Referring to the drawings: Figure 1 is a plan view of a holder embodying my invention. Fig. 2 is a side elevation of the same illustrating a calendar pad attached thereto, portions of the leaves of said pad being shown supported by the base while other portions thereof are shown supported against the back of said holder. Fig. 3 is a section taken on the line 3-3 of Fig. 2 25 illustrating the manner in which the leaf guiding members interlock and are detachably secured to the base. Fig. 4 is a rear elevation of the holder illustrated in Figs. 1 and 2, portions of the base thereof being 30 broken away and shown in section to more clearly illustrate the manner in which the supporting members for the back interlock with said base. Fig. 5 is a side elevation of a modified form of holder.

40 In the drawings, 6 is a base formed from sheet material, preferably metal, and substantially rectangular in form. The rear portion of said base is bent at 7 downwardly and slightly rounded at the end as at 8 to 45 position and to maintain the body portion of said base inclined. A back 9 also formed of material similar to said base is mounted upon said base and at an angle thereto, said base and said back being constructed and 50 arranged to support a calendar pad 10. The back 9 is preferably fastened to said base by means consisting of a tongue 11 formed at the lower end of said back and being constructed and arranged to fit a perforation or slot 12 provided in said base adjacent the rear end thereof and extending

transversely of said rear end. Means have been provided on said tongue 11 to lock said tongue within said slot. These means are formed by cutting inwardly from opposite 60 sides of said tongue at 13, 13 to form partially detached portions of material 14, 14, which portions are then bent substantially at right angles to said tongues to engage the under side of said base. 65

The leaves of the calendar pad 10 are guided from the base to the back by leaf guiding members 15, preferably two in number. These guiding members are resilient and are formed integral with said back 9 70 75 preferably by slitting or cutting the material constituting said back longitudinally thereof, thus partially detaching portions of said material. These partially detached portions are then bent forwardly as at 16, thence downwardly at 17 and interlock with 75 said base at the lower extremities thereof, said members passing through perforations in said calendar pad.

The leaf guiding members 15 preferably 80 detachably interlock with the base within slots 18, said slots being of a length sufficient to permit said guiding members to be inserted therein, but slightly nearer together than are said guiding members thus necessitating the contracting of the lower ends of said guiding members during such an insertion. The lower ends of said guiding members are provided with incisions 19 85 extending from opposite outer edges inwardly 90 for a portion of the width of said members. These incisions permit the guiding members to expand to their normal positions when said incisions aline with the material at the outer ends of the slots 18. 95

The back 9 is provided with supporting members 20, preferably two in number. These members are formed integral with said back and in a manner similar to that in which the guiding members 15 are formed, that is, by partially detaching portions of the material from which the back is constructed. Said supporting members 20 are bent rearwardly from said back and downward to the base 6 adjacent the bend 7 where they interlock with said base, said supporting members having incisions 21 extending from the inner edges thereof outwardly transversely of said members for a portion 100 of the width thereof. 105

The base 6 is also provided with incisions or cuts 22 which are adapted to receive the 110

uncut portions 23, thus permitting the outer edges 24 of said supports to lie flush and aline with the adjacent edge of the base 6. The extremities of the supporting members 20 are preferably extended to a point alining with the forward end 25 of the base 6 and the rounded portion 8 of the depending or bent end of said base and are bent to form pieces 26, thus providing other supports for said base intermediate the opposite ends thereof. By reason of so many supports therefor the material from which said base is constructed may be very much thinner than that which is usually employed for calendar pad holders constructed of sheet material. The base 6 is also ribbed longitudinally as at 27, 27 to provide reinforcements therefor.

Another support for the base 6 may be provided, if desired, to be used either with or without the extension of the supporting members 20 and consists in extending the tongue 11 downwardly as at 29 into engagement with the surface upon which the pad holder is resting. This extension may be widened, if desired, as shown in dotted lines Fig. 4 to provide a firmer and more stable support for the base beneath the pad 10. The invention however is not limited to the use of all of the supports for the base referred to, but any of them may be eliminated without departing from the spirit and scope of the invention.

It will also be evident that by providing the supports 20, leaf guiding members 15, and extending the back to and into interlocking engagement with the base, the back will be rigidly supported also permitting very light metal to be used in forming the back without endangering the substantiality of the holder.

Fig. 5 illustrates a modified form of holder. In this form the back 9' is constructed substantially as illustrated in Figs. 1, 2, 3 and 4. The supporting members 20' are however bent at 28 rearwardly extending beyond the upper end of the back 9', thus providing a support for the upper or rear end of the base 6'. The downwardly projecting portion at the rear of the base constituting a support therefor, illustrated in Figs. 1 and 2, is eliminated from the base illustrated in Fig. 5 and the material constituting said base terminates immediately at the rear of the interlocking point between said supports 20' and said base. The holder when constructed of very light material, as described, may be shipped flat with the pad 10 and erected by the purchaser or the recipient thereof.

When it is desired to replace the calendar, which is on the holder, by a new one, the lower extremities of the leaf guiding members 15 are contracted and withdrawn from the slots 18, then bent upwardly clear of the

base sufficiently to permit the leaves of the pad to be removed therefrom and a new pad is then slipped on to said guiding members and said members inserted in the slots 18 and permitted to expand and interlock with the base.

Having thus described my invention what I claim and desire by Letters Patent to secure is:

1. A device of the class described having, in combination, a base, a back connected with and disposed at an angle to said base, a support for said back extending therefrom rearwardly into engagement with said base, and leaf guiding means extending from said back forwardly into engagement with said base. 75

2. A device of the class described having, in combination, a base provided with a perforation adjacent one end thereof, a back constructed of sheet material and arranged to fit said perforation, a portion of said back being bent to secure said back within said perforation, means on said back extending through said base and constituting a support therefor, and leaf guiding means extending from said back to said base. 85

3. A device of the class described having, in combination, a base formed of sheet material and provided with a perforation, a back also formed of sheet material and provided with a tongue adapted to project through said perforation, means on said tongue constructed and arranged to be bent laterally relatively thereto to secure said tongue within said perforation, and leaf guiding means formed integral with said back by partially detaching portions of the material thereof, said leaf guiding means being constructed and arranged to interlock 105 with said base.

4. A device of the class described having, in combination, a base formed from sheet material, a back also formed from sheet material and constructed and arranged to interlock with said base, a pair of supporting members for said back, said supporting members being formed integral with said back and adapted to interlock with said base at the rear of the interlocking point 110 of said base and said back, and leaf guiding means formed integral with said back and constructed and arranged to interlock with said base at a point in front of said back. 115

5. A device of the class described having, in combination, a base formed from sheet metal and provided with a slot adjacent one end thereof, a back also formed from sheet metal and provided with a tongue adapted to fit said slot, portions of said tongue being constructed and arranged to lock said tongue within said slot, a pair of leaf guiding members formed integral with said back and extending forwardly from said back into interlocking engagement with said base, 125 130

and a pair of supporting members formed integral with said back and adapted to interlock with said base at the rear of said back, said supporting members being constructed and arranged to support said base.

6. A device of the class described having, in combination, a base formed from sheet material, a portion of said material being bent downwardly at the rear of said base to form a support therefor, a back also formed of sheet material and interlocking with said base, a pair of resilient leaf guiding members formed integral with said back and extending forwardly therefrom into detachable engagement with said base, and a pair of supporting members formed integral with said back and extending therefrom rearwardly, said base having transversely disposed incisions adapted to receive and interlock with said supporting members, said supporting members being also arranged to support the rear end of said base.

7. A device of the class described having, in combination, a base having supports at opposite ends, said base being provided with a perforation intermediate said ends, a back provided with a tongue adapted to project through said perforation downwardly and

terminating substantially in alinement with the extremities of the supports at opposite ends of said base, said extension also constituting a support for said base, and leaf guiding means extending from said back to said base.

8. A device of the class described having, in combination, a base having supports at opposite ends, said base also being provided with a perforation intermediate said ends, a back provided with a tongue adapted to project through said perforation downwardly and terminating substantially in alinement with the extremities of the supports at opposite ends of said base, said extension also constituting a support for said base, means on said tongue adapted to secure said tongue within said perforation, and leaf guiding means extending from said back to said base.

In testimony whereof I have hereunto set my hand in presence of two subscribing witnesses.

WILLIAM A. SPURRIER.
